ENGINE STARTING MECHANISM

Romeo M. Nardone, East Orange, N. J., assignor
to Eclipse Aviation Corporation, East Orange,
N. J., a corporation of New Jersey

Application March 17, 1934, Serial No. 716,199

13 Claims. (Cl. 123—179)

This invention relates to engine starting mechanism and more particularly to means for controlling both the energization of such a starting mechanism and the establishment of driving connection between the mechanism and the engine to be started.

In many types of engine starting devices, it is desirable to provide mechanism which is normally disengaged from the engine to be started, but shiftable into engagement therewith by means functioning more or less independently of the prime actuating instrumentalities of the starter. Thus, for example, in many types of automobile starters there is employed a so-called manual shift in which a pinion, or equivalent engine engaging member, is shifted to the working position by a lever or other means under the control of the operator even before any rotation of the starter prime mover. In other cases, as for example, in engine starters of the inertia type, such as that disclosed in the Lansing Patent No. 1,833,948, electromagnetic means distinct from the starter prime mover serve to actuate the engine engaging clutch entirely independently of and in fact only after such prime mover has been de-energized. That is, the prime mover (shown as an electric motor in the aforesaid Lansing patent, and similarly shown in the preferred embodiment of the present invention) is first energized for a period of time sufficient to accelerate the starter flywheel (constituting the inertia element of the device) to the desired speed, whereupon switch mechanism is manually operative to de-energize the motor and at the same time energize a solenoid which actuates the engine engaging element.

The present invention constitutes an improvement on the controlling means and method of operation of the above identified patent in the sense that instead of de-energizing the motor concurrently with the meshing (engine engaging) operation, the motor is caused to remain energized even after meshing is effected, and the energy stored in the starter flywheel is held in reserve for use only after a period of cranking directly from the motor to the engine. Such preliminary period of direct cranking by the motor, with the flywheel disconnected, relieves the flywheel of the comparatively heavy drain upon its stored energy which it ordinarily undergoes by reason of the high resistance of the engine parts during the "breakaway" effort. By delaying the coupling of the energized flywheel until such breakaway resistance has been overcome, the cranking period is lengthened to an

extent corresponding to the saving in energy, since the flywheel will then deliver up its energy at a much steadier and more gradual rate.

Other objects of the invention are to provide novel and improved means for controlling the operation of the inter-related parts employed in a device of the class described, and in the specific construction and inter-relation of such parts, while further objects will appear more fully from an examination of the following detailed description when read with reference to the accompanying drawings showing one embodiment of the present invention.

It is to be understood, however, that the drawings are merely illustrative and are not designed to indicate the limits of the invention, reference being had for this purpose to the appended claims.

In the drawings there is shown in Fig. 1 a representation, partly in section and partly in outline of one type of engine starting mechanism to which the present invention is applicable.

Fig. 2 is a view in perspective of one of the clutch actuating devices.

Fig. 3 is a diagram of the control circuits and parts; and

Figs. 4-8 show different relative positions of the parts.

Referring to the drawings, the starter mechanism is shown as embodied in a casing 4, wherein is rotatably mounted an inertia element or flywheel 5 which may be automatically rotated by an electric motor 6, or which may be manually rotated by means of a shaft terminating in the bevel gear 7. The flywheel is adapted to drive a clutch member 8 through suitable mechanism mounted in housing 4, and when said flywheel has been brought to a sufficiently high speed of rotation, clutch member 8 is adapted to be thrown into engagement with a corresponding clutch member 9 provided on the shaft 10 of the engine to be started. The connections between the flywheel 5 and the driven member 8 may be of any desired form including reduction gears 16, 17, 18 and 19 and torque limiting clutch mechanism 45 as illustrated and described in greater detail in Fig. 4 of the Lansing patent above identified.

The present arrangement differs from that of the aforesaid Lansing patent however, in that the driving connection from the motor 6 to the flywheel 5 includes a gear train and a disengageable clutch whereby the flywheel may be first accelerated by the delivery thereto of energy developed in the motor 6, and thereafter the flywheel allowed to run free of the gear train and

motor so that the said gear train and motor may function to directly crank the engine member 9, the effectiveness of the flywheel as a driving agency being thus delayed until after a preliminary period of direct cranking. As shown the gear train includes the elements 16 and 17 above referred to and also a pair of beveled gears 23 and 24, the latter being shown rigidly secured by means 26 to the gear 17 while the former is shown as integral with a short shaft 28 splined at its upper end to a cup shaped element 29 constituting the driven member of an overrunning clutch having driving rollers 31 and a driving inner race 32 splined to the lower portion 33 of the armature shaft 34 of the motor. The disengageable clutch is shown in the form of a pair of cooperating conical surfaced friction elements 37 and 38, the former being shown as riveted to the flywheel 5 and the latter as secured within the rim 39 of a cup shaped member 41 having a hub 42 drivably connected as by splines to a splined portion of shaft 43, the said shaft as shown being integral as above described with pinion 16. A coil compression spring 51 is mounted within the hub 42 and since one end of the spring abuts a plate 52 bearing against the inner race of axially fixed bearing 53, it is apparent that the spring tends to engage the clutch members 37 and 38 and hold said members in engagement except when released by the means to be described.

Preferably the means for releasing the clutch elements 37 and 38 is inter-related with the means for energizing the motor 6 and also the means for throwing the engine engaging member 8 into engine engaging position. As shown diagrammatically in Fig. 3 the inter-related mechanism includes a rod 56 (also shown in Fig. 1) connecting with the clutch member 8 and operable in the same manner as is the corresponding rod in the aforesaid Lansing patent, the operating means including a torsion spring 51, one end of which engages the rod 56 and the other end of which abuts boss 59 of the housing and thereby tends to hold the clutch in the position indicated in both Figs. 1 and 3. The controlling mechanism as best viewed in Fig. 2 further includes a rod 60 pivotally connected to a lever 61 which in turn operatively engages a shaft 62 connecting with a yoke member 55 having eccentric or cam portions at its ends in the form of inwardly directed pins 65 and 68 engageable with the collar 66 which surrounds the hub 42 and operates through thrust bearings 68 to move said hub and hence the clutch 39 to the right in Fig. 1 in response to movement of the rod 60 to the left. As shown in Fig. 3, one portion of the rod 60 receives a cylindrical member 63 preferably of a non-conducting material and said member 63 in turn connects with a conducting disc 64 adapted to bridge either of two sets of contacts 66 and 67, the former set being in series with the winding of the motor 6 indicated in Fig. 3 and the latter set being in series with the winding 69 of a solenoid, the movable core of which is extended to pass through a dash-pot 71 constituting an adjustable time delay device, the lower end of the movable element of the dash-pot being also shown in the form of a rod 72 connecting with the previously described clutch actuating rod 56 through the instrumentality of a bell crank 73. A spring pressed detent 76 is engageable with a depression 77 in the rod 60 as shown in Figs. 6 and 7 but is normally out of engagement therewith as indicated in Figs.

4, 5 and 8. Suitable manually operable means controlling the switches 66 and 67 and hence the flow of current from a suitable source 79, is shown in the form of a rod 82 terminating in a knob 83 located within convenient reach of the operator of the vehicle.

Having thus described the parts entering into the preferred embodiment of the invention as shown, the operation thereof will be seen to be as follows:

Prior to commencement of the cycle, the elements 60 and 82 are in the position indicated in Fig. 4 in which position the spring 51 holds clutch 37-39 engaged while spring 57 holds engine engaging member 8 in the disengaged position. Now, upon movement of knob 83 to the position shown in Fig. 5 current is caused to flow from the battery 79 into the motor 6 by way of connections 91, 92 and 93. The resulting rotation of the armature shaft 34 is communicated to the 20 flywheel 5 through elements 29, 28, 23, 17, 16, 43, 42, 39 and 37, and the flywheel is thus accelerated to the desired speed. When such desired speed is attained, knob 83 is moved further to the left into the position indicated in Fig. 6 and such movement is communicated to the rod 60 by reason of engagement of the end of cylinder 63 with the shoulder 95 on the rod 60. Such movement operates through the lever 61 and collar 66 to disengage clutch 37, 39, and the clutch is locked in 30 the disengaged position by the action of detent 76 upon depression 77.

At the same time the circuit to the motor 6 is broken and the solenoid 69 energized, due to the shifting of disc 64 from the position shown in Fig. 5 to the position shown in Fig. 6. Energization of solenoid 69 operates through links 72, 73 and 56 to move member 8 into mesh with engine member 9 whereupon the motor 6 is again energized (the flywheel clutch 37, 39 remaining open) 40 by action of the operator in returning knob 83 to the position shown in Fig. 7. After the resulting direct cranking from motor 6 to engine member 9 (through the gear train) has proceeded for a time, the operator will pull knob 83 still further 45 to the right, and into the position shown in Fig. 8. In this latter position detent 76 is no longer effective to hold clutch 37, 39 open, and said clutch is therefore engaged by action of spring 51. The flywheel 5 now discharges its energy through the 50 clutch, shaft 43, and the gear train 16, 17, 18 and 19, to complete the cranking of the engine member 9. When the latter overruns starter member 8 spring 57 (in conjunction with the usual reverse screw action) acts to de-mesh the starter, the 55 de-meshing being preferably controllably retarded by the setting of adjusting valve 98 of the dash-pot 71 in order to guard against a premature de-meshing—that is, to prevent de-meshing in cases where the overrunning of member 9 is 60 merely momentary, such as might result from an isolated firing impulse.

There is thus provided novel means whereby an engine starter may be quickly energized and thereafter thrown into mesh with the engine to 65 be started, said means being so constituted that the flywheel may be selectively rotated electrically or manually and the meshing mechanism for starter jaw 8 is likewise so constituted that manually operable means may be connected, if 70 desired, to the lever 72. It is accordingly to be understood that the invention is not limited to the embodiment illustrated and described, since various changes may be made in the details of construction and arrangement of parts without 75

departing from the invention defined in the following claims.

What is claimed is:

1. In an engine starter, in combination with an engine engaging member, a rod operative to move said engine engaging member into engine engaging position, a motor operative to rotate said engine engaging member both before, during and after actuation of said rod, an inertia member energizable in response to operation of said motor, means for transferring the energy of the inertia member to said engine engaging member, and means forming part of the drive from said motor to the inertia member for completely severing the drive between the inertia member and the engine engaging member and thereby preventing the transfer of such energy either before or after actuation of said rod.
2. In an engine starter, in combination with an engine engaging member, a rod operative to move said engine engaging member into engine engaging position, a motor operative to rotate said engine engaging member both before, during and after actuation of said rod, an inertia member energizable in response to operation of said motor, means for transferring the energy of the inertia member to said engine engaging member and means forming part of the drive from said motor to the inertia member for preventing any such energy transfer.
3. In an engine starter, in combination with an engine engaging member, a rod operative to move said engine engaging member into engine engaging position, a rotating means operative to rotate said engine engaging member both before, during and after actuation of said rod, an inertia member energizable in response to operation of said rotating means for transferring the energy of the inertia member to said engine engaging member, and means forming part of the drive from said motor to the inertia member for completely severing the drive between the inertia member and the engine engaging member and thereby preventing the transfer of such energy either before or after actuation of said rod.
4. In an engine starter, in combination with an engine engaging member, a rod operative to move said engine engaging member into engine engaging position, a rotating means including a motor and reduction gearing operative to rotate said engine engaging member both before, during and after actuation of said rod, an inertia member energizable in response to operation of said rotating means to receive and subsequently transfer the energy of the inertia member to said engine engaging member and means independent of said rod for preventing any such energy transfer, said means including a single clutch which, in the disengaged position, disconnects said inertia member from both said motor and said reduction gearing.
5. In an engine starter, in combination with an engine engaging member, a shifter element operative to move said engine engaging member into engine engaging position, a motor operative to rotate said engine engaging member both before, during and after actuation of said shifter element, an inertia member energizable in response to operation of said motor, means for transferring the energy of the inertia member to said engine engaging member, and means forming part of the drive from said motor to the inertia member for completely severing the drive between the inertia member and the engine engaging member and thereby preventing the

transfer of such energy either before or after actuation of said shifter element.

6. In an engine starter, in combination with an engine engaging member, a shifter element operative to move said engine engaging member into engine engaging position, a motor operative to rotate said engine engaging member both before, during and after actuation of said shifter element, an inertia member energizable in response to operation of said motor, means for transferring the energy of the inertia member to said engine engaging member and means forming part of the drive from said motor to the inertia member for preventing any such energy transfer.

7. In an engine starter, in combination with an engine engaging member, a shifter element operative to move said engine engaging member into engine engaging position, a rotating means operative to rotate said engine engaging member both before, during and after actuation of said shifter element, an inertia member energizable in response to operation of said rotating means for transferring the energy of the inertia member to said engine engaging member, and means forming part of the drive from said motor to the inertia member for completely severing the drive between the inertia member and the engine engaging member and thereby preventing the transfer of such energy either before or after actuation of said shifter element.

8. In an engine starter, in combination with an engine engaging member, a shifter element operative to move said engine engaging member into engine engaging position, a rotating means operative to rotate said engine engaging member both before, during and after actuation of said shifter element, an inertia member energizable in response to operation of said rotating means for transferring the energy of the inertia member to said engine engaging member and means forming part of the drive from said motor to the inertia member for preventing any such energy transfer.

9. The method of operating an engine starter of the type having an engine engaging member, a rod operative to move said engine engaging member into engine engaging position, a prime mover and an inertia member energizable in response to operation of said prime mover, which includes the steps of first energizing the inertia member, then causing it to run idly while the rod is operated and the engine cranked directly by the prime mover acting through the agency of the engine engaging member, and thereafter causing the transfer to the engine of the energy previously stored in the inertia member.

10. The method of operating an engine starter of the type having an engine engaging member, a prime mover and an inertia member energizable in response to operation of said prime mover, which includes the steps of first energizing the inertia member, then causing it to run idly while the engine is cranked directly by the prime mover acting through the agency of the engine engaging member, and thereafter causing the transfer to the engine of the energy previously stored in the inertia member.

11. The combination with an engine engaging member, electric motor, flywheel and gear train connecting all three elements, whereby energy developed in the motor may be delivered directly to either the engine engaging member, flywheel, or both, of a means including a clutch control-

ling connection of said flywheel with said gear train, a switch movable to interrupt the flow of current to said motor, and means movable by said switch to cause release of said clutch.

12. The combination with an engine engaging member, electric motor, flywheel and gear train connecting all three elements, whereby energy developed in the motor may be delivered directly to either the engine engaging member, flywheel, or both, of means including a clutch controlling connection of said flywheel with said gear train, a switch movable to interrupt the flow of current to said motor, and means movable by said switch to cause release of said clutch, said switch further operating to cause engine engaging movement of said engine engaging member, but only after release of said clutch.

13. The combination with an engine engaging member, electric motor, flywheel and gear train connecting all three elements, whereby energy developed in the motor may be delivered directly to either the engine engaging member, flywheel, or both, of means including a clutch controlling connection of said flywheel with said gear train, a switch movable to interrupt the flow of current to said motor, and means movable by said switch to cause release of said clutch, said switch further operating to cause engine engaging movement of said engine engaging member, but only after release of said clutch, and resilient means to re-engage said clutch prior to the return movement of said engine engaging member. 15
